UNITED STATES PATENT OFFICE.

ARTHUR F. BERGER, OF HOLDEN, WEST VIRGINIA.

CABLE-HOOK.

1,106,183.

Specification of Letters Patent. Patented Aug. 4, 1914.

Application filed July 18, 1913. Serial No. 778,853.

To all whom it may concern:

Be it known that I, ARTHUR F. BERGER, a citizen of the United States, residing at Holden, in the county of Logan, State of West Virginia, have invented certain new and useful Improvements in Cable-Hooks; and I do hereby declare the following to be a full, clear, and exact description of the invention, such as will enable others skilled in the art to which it appertains to make and use the same.

This invention relates to cable hooks for use in connection with gathering locomotives or the like and has for an object to provide a hook of this character having a fuse which will blow upon overload and prevent damage.

A further object is to provide a hook of this type in which the fuse will be easy of access.

A further object is to provide an extremely simple and inexpensive hook of this type which will be strong and durable and will be formed of a few parts that will not easily get out of order.

With the above objects in view the invention consists of certain novel details of construction and combination of parts herein-after fully described and claimed, it being understood that various modifications may be made in the minor details of construction within the scope of the appended claims.

In the accompanying drawing illustrating this invention:—Figure 1 is an end elevation of the hook showing its application to a trolley wire. Fig. 2 is a front elevation with the cover plate removed. Fig. 3 is a longitudinal sectional view taken on the line 3—3 Fig. 2. Fig. 4 is a cross sectional view taken on the line 4—4 Fig. 1.

Referring now to the drawing in which like characters of reference designate similar parts, 10 designates a stock of wood, fiber, or any similar material, which is provided at one end with a grip 11, and is provided in one side with a recess 12 which extends nearly from end to end of the stock, there being an opening 13 through one end of the stock for the reception of the trolley wire end 14, and there being an opening 15 through the opposite end of the stock and grip for the reception of the insulated conductor cable 16.

Disposed on the inner wall of the recess 17 is a terminal in the nature of a copper plate 18 upon which the hook 14 is secured by

means of a screw 19 and also by means of a copper clamp plate 20 which is secured by spaced bolts 21 to the stock as shown in Fig. 4. Disposed on the inner wall of the recess is a second terminal in the nature of a copper plate 21 upon which the eye 22 of the conductor wire 16 is secured by means of a bolt 23, the wire being further secured by a copper clamp plate 24 which is secured to the stock by spaced bolts 25.

An ordinary lead strip fuse 26 has the terminals notched and such notched ends clamped to the copper plates 17 and 21 by means of nuts 27 on the bolt 28 passed through the plate 17 and by means of nuts 29 disposed on the above mentioned conductor wire securing bolt 23. Upon an overload, the fuse will blow and thus prevent damage, as will be understood. Directly under the fuse between the terminals is a non-heat conducting plate 30 formed of insulating material and secured to the stock by means of screws 31, the ends of the plate being notched as shown at 32 and 33 to receive the terminals 17 and 21. A cover plate 34 is secured at the ends to the stock by screws 35, and upon the removal of the latter access to the terminals may be easily effected by replacing a blown fuse with a new one.

From the above description it will be seen that I have provided an extremely simple device of the class described which is inexpensive to manufacture and is formed of a few simple parts that will not easily get out of order.

What is claimed, is:—

1. The combination in a collecting hook for locomotive or other electric machinery of a stock of non-conducting material having a recess in one side face and a longitudinal passage communicating with the recess and opening through one end of the stock, a metallic plate on the bottom wall of said recess, a hook engaged through said passage and bearing upon the outer face of said plate, and a securing device anchoring said hook to the plate, said device being accessible through the recess to permit removal of the hook.

2. The combination in a collecting hook for locomotives, of a stock of non-conducting material having a recess in one side face and longitudinal passages entering said recess and opening through opposite ends of the stock respectively, one of said passages be-

ing disposed obliquely to the longitudinal axis of the stock, a metallic plate on the bottom of said recess near the inner end of each of said passages, a fusible connection between said plates, a hook passed through the obliquely disposed passage and having its inner end secured to the adjacent plate, and a conductor wire extending through the

other passage and connected to the other plate.

10

In testimony whereof, I affix my signature, in the presence of two witnesses.

ARTHUR F. BERGER.
